UNITED STATES PATENT OFFICE

LEWIS C. TRAVERS, OF GARDNER, MASSACHUSETTS, ASSIGNOR TO P. DERBY COMPANY,
OF GARDNER, MASSACHUSETTS, A CORPORATION OF MASSACHUSETTS

DESIGN FOR A COMBINED DESK AND CHAIR SUPPORT

Application filed April 30, 1932. Serial No. 43,669. Term of patent 3½ years.

To all whom it may concern:

Be it known that I, LEWIS C. TRAVERS, a citizen of the United States, residing at Gardner, in the county of Worcester and State of Massachusetts, have invented a new, original, and ornamental Design for a Combined Desk and Chair Support, of which the following is a specification, reference being had to the accompanying drawing, forming part thereof.

The figure is a perspective view of a combined desk and chair support showing my new design.

I claim:

The ornamental design for a combined desk and chair support as shown.

LEWIS C. TRAVERS.
